DIPPER TOOTH ASSEMBLY

Donald H. Young, San Francisco, Calif., assignor
to American Manganese Steel Company, Chi-
cago, Ill., a corporation of Maine

Application April 5, 1933, Serial No. 664,549

1 Claim. (Cl. 37—142)

This invention relates to improvements in dipper teeth and particularly to dipper teeth in which the points are replaceable and reversible with respect to the base portions of the teeth.

Various forms of dipper teeth designs have been proposed in which a dipper tooth point is pulled upon the base portion by a wedging pin. The point is customarily formed with a pair of rearwardly divergent jaws and it is necessary to provide a shank or a pair of tangs rearwardly extending from the point and fitting into the base for cooperation with the wedge pin. The dipper teeth in use are subject to heavy digging strains which tend to loosen the dipper points from the bases or to distort the connecting portions so that loosening or breakage of the teeth finally occurs.

It is an object of the present invention to provide in improved design in which the connecting portion is so designed that, although heavy digging strains may cause distortion of the forward portion of the point, the connecting portions of the point and base will remain in tight engagement without distortion.

It is a particular object of my invention to disclose a construction in which a part of a dipper tooth is provided with a pair of separated attaching portions fitting into pockets formed in the other form of the tooth, the two parts being provided with tapered contacting surfaces whereby the attaching portions are wedged together and therefore held in tight engagement.

Further objects and advantages of the present improvements will be more readily apparent from the following description taken in connection with the attached drawings.

In the drawings:

Figure 1 is a plan view of the dipper tooth assembly;

Figure 2 is a side elevation;

Figure 3 is a longitudinal section on the plane indicated 3—3 in Figure 1;

Figure 4 is a longitudinal section on the plane indicated 4—4 in Figure 2;

Figure 5 is a detail cross section on the plane indicated 5—5 in Figure 3;

Figure 6 is a detail section on the plane indicated 6—6 in Figure 3;

Figure 7 is a plan view of a modified construction;

Figure 8 is a side elevation;

Figure 9 is a longitudinal section on the plane indicated 9—9 in Figure 7;

Figure 10 is a longitudinal section on the plane indicated 10—10 in Figure 8, and

Figures 11 and 12 are detail sections on the

planes indicated, respectively, 11—11 and 12—12 in Figure 8.

Referring first of all to the form disclosed in Figures 1 to 6, inclusive, the dipper tooth assembly includes a base 10 and a point 12, these parts being held together by a wedge pin 14. The base 10 includes rearwardly extending shanks 16 and 18 for attachment of the base to the usual dipper front, which is received in the recess 20 between the shanks. The base has forwardly convergent top and bottom walls 22 and 24 and vertical side walls 26. The side walls have forwardly extending V-shaped cheeks 28. The base has a cored opening 30 extending therethrough from the nose to the recess 20. The side walls 26 and the nibs 28 are tied together by a horizontal web 32 extending within the cored opening 30 and extending forwardly to the end of the cheeks 28, as shown at 34 in Figure 4. The forward portions 35 of the cheeks have tapered side faces 36 for cooperation with the point as will be later described. The inside faces of the cored opening 30 above and below the web 32 are tapered slightly rearwardly toward each other, as indicated at 38 in Figure 3. The upper part of the base 24 is provided with a slotted opening 40 extending into the cored opening 30 and the bottom face of the base is provided with a slotted opening 42. These openings 40 and 42, together with an opening 44 in the web 32 are tapered and adapted to receive the wedge pin 14. As shown in Figure 3 the wedge pin, when in position, fits tightly against the forward sides of the openings 40, 42 and 44.

The point 12, which is fitted on the base, is formed with rearwardly divergent jaws 46 and is adapted to be mounted reversibly as well as replaceably upon the base. The jaws 46 are strengthened by partial side walls 48 whereby a pocket is formed to the portions 35 of the base. Rearwardly of the walls 48 however the point is open to abut against the cheeks 28 of the base, as shown clearly in Figure 2. The pocket in the point between the jaws 46 and the side walls 48 receives the web portion 32 of the base.

Integrally formed with and rearwardly extending from the jaws 46 are provided attaching tang portions 50 which are spread apart to fit loosely over the web 32 on the base but have tapered outer faces adapted to tightly engage the inside tapered surfaces 38 of the base. The tangs 50 have tapered slotted openings 52 to receive the wedge pin 14 and in assembled position the wedge pin will be forced tightly against the rear faces of the openings 52 as shown in Figure 3. Thus the point is assembled upon the base by move-

ment longitudinally into position whereupon the tangs 50 will be pressed toward each other and wedge tightly into engagement with the inside tapered faces of the cored portion 30 of the base, 5 thereby wedging the point against movement transverse to the dipper front, while, at the same time, the side walls 48 of the point will be wedged against the tapered side faces 36 of the base, thereby wedging the point against lateral movement with respect to the base. It is obvious that 10 driving the wedge pin into position will rigidly secure the point and base together since the point will be pulled more tightly into position by the action of the wedge pin.

15 In assembled position the wedge pin is seated against the base at three spaced faces and against the point at two spaced faces, therefore the wedge pin is under double shear. The sectional view of Figure 5 shows the manner in which the nose portion of the base, which is I-shaped in cross section at this point, fits closely within the pocket formed in the point. The sectional view of Figure 6 on the other hand illustrates the manner in which the tang portions 50 of the point fit 20 tightly into the openings formed in the base above and below the web 32.

25

In the modified construction disclosed in Figures 7 to 12, the base 110 and point 112 are joined together by the wedge pin 114. The base has attaching shank portions 116-118 having a recess 120 therebetween adapted to receive the dipper front and a short web 121 between the shanks is adapted to fit into a slot in the front wall. The top and bottom faces 122-124 of the 30 base taper forwardly toward each other. The base has vertical side walls 126. The side walls of the base have forwardly projecting V-shaped portions 128 adapted to cooperate with the point 112 as will be later described. The interior of 35 the base portion is recessed to provide pockets 130 separated by the horizontal web or tongue 132, which integrally connects the side walls. The web 132 extends to the ends of the V-shaped portions 128 but is slotted or indented at its central 40 portion as at 133, as clearly shown in Figure 10. The side walls of the pocket 130 are tapered slightly rearwardly as indicated at 135, while the top and bottom walls of the pockets 130 respectively are tapered as indicated 138. The wedge 45 pin 114 is received in the slotted opening 140 formed in the upper part of the base, opening 142 in the lower part of the base and opening 144 in the web 132, whereby the wedge pin seats against the forward faces of the openings when the dipper tooth is assembled.

50 The point 112 has rearwardly extending tapered jaws 146 which engage the tapered side walls 128 of the base. Rearwardly extending from the point and from between the jaws 146 are a pair of attaching tangs 150 provided with openings 152 to receive the wedge pin, whereby the rear faces of the openings 152 seat against the wedge pin.

55 The tangs 150 have tapered walls cooperating with the interior tapered walls of the pockets 130 in the base but the space between the tangs is

somewhat wider than the thickness of the web 132 on the base whereby the tangs are free to be wedged together as the point is drawn upon the base thereby obtaining a tight engagement at the contacting surfaces 138. The strength of the point is materially increased by the provision of a short connecting web 154 as shown in Figure 10. This web 154 is narrower than the width of the tangs 150 and is illustrated in the sectional view of Figure 11.

60 Thus, in this design, the divergent jaws of the point are prolonged into tapered extensions or tangs which are adapted to receive the wedge which holds the point and base in engagement. The base prevents the spreading of the jaws by contact with the tapered outer surfaces of the jaw extensions or tangs. These tapered surfaces of the extensions are so arranged that if the point is pressed into engagement with the base a wedging action is obtained which causes the 15 jaws of the point to be held in close engagement with the forward end of the base. In order to prevent the forward end of the base from being unduly weakened, due to its bifurcated formation, it is provided with the lateral web 132 uniting the side portions and producing in effect an I-beam section. This web 132 is indented as by the slot 133 to permit the provision of the short connecting web 154 between the divergent jaws of the point. The dimensions of this web 154 are 20 such that each section of the point will have a greater resistance against the imposing bending strains than the moment of these strains at the section considered. This same consideration is true of the forward end of the base where the 25 two side projecting portions are independent of one another only for such a distance as will produce sections of greater strength than the corresponding bending moments. The result of this assembly is that the point and the portion of 30 the base which engages the same form a beam of greater than uniform strength for the resistance of both vertical and lateral bending strains. It has been found in actual use that the forward or digging end of the point, if subjected to undue 35 strain, will be distorted by bending without any corresponding distortion of the base or rear sections of the point.

40 I claim:

45 In a dipper tooth assembly, a point having 50 rearwardly divergent jaws, spaced side walls joining said jaws forming a pocketed crotch in said point, a pair of tangs rearwardly extending from said jaws, a base having spaced side walls adapted to extend into the pocketed crotch of said point 55 between the side walls of said point, a web integral with said base connecting said side walls and adapted to extend between the tangs of said point, said base having openings in the body thereof to receive the rear ends of said tangs and a wedge pin extending into said base through said web and through the rear ends of said tangs 60 directly engaging said tangs for forcing said point into tight engagement with said base.

65 DONALD H. YOUNG.
